UNITED STATES PATENT OFFICE.

PARKER B. HASKELL, OF LYNN, MASSACHUSETTS, ASSIGNOR OF ONE-THIRD TO WALTER B. POHLE, OF LYNN, MASSACHUSETTS, AND ONE-THIRD TO SUSAN V. RUSSELL, OF CHELSEA, MASSACHUSETTS.

SEDIMENT COLLECTOR FOR SPLASH TROUGHS.

Application filed February 6, 1925. Serial No. 7,334.

To all whom it may concern:

Be it known that I, PARKER B. HASKELL, a citizen of the United States of America, and a resident of Lynn, in the county of Essex, in the State of Massachusetts, have invented certain new and useful Improvements in Sediment Collectors for Splash Troughs, of which the following is a specification.

- 10 This invention relates to splash troughs such as are used in the crank casings of certain internal combustion engines, and has for its object the provision of means whereby the sediment in the oil in the trough may be collected in a member positioned in a chamber in said trough and removable from the trough through the wall of the crank casing. This object is attained by the mechanism illustrated in the accompanying drawing.
- 15 For the purpose of illustrating the invention, one preferred form thereof is illustrated in the drawings, this form having been found to give satisfactory and reliable results, although it is to be understood that 20 the various instrumentalities of which the invention consists can be variously arranged and organized, and the invention is not limited to the precise arrangement and organization of these instrumentalities as herein shown and described except as required by the scope of the appended claims.

Of the drawings—

Figure 1 represents a section of a crank casing having formed integral therewith a splash trough provided with a removable sediment collector embodying the principles of the present invention.

Figure 2 represents a section on line 2, 2 on Fig. 1, and

Figure 3 represents a section of the crank casing and showing one sediment collector being removed from the trough by the insertion of another collector.

Similar characters indicate like parts throughout the several figures of the drawings.

In the drawings 10 is a crank casing of an internal combustion engine having formed integral therewith a trough 11 and a bottom 12 below said trough.

The oil retaining compartment 13 of the trough 11, by means of an opening 14, com-

municates with a chamber 15 extending transversely of the casing 10 and open at its opposite ends.

Each end of the chamber 15 is slightly enlarged and threaded to receive a closure 16.

The oil retaining compartment is partially filled with oil and in the operation of the engine the free end of the crank 17 passes through this oil and thoroughly lubricates the bearing between the crank 17 and the connecting rod 18.

The crank 17 is secured to and rotates with the shaft 19.

Sediment is liable to collect in the oil and if this gets into the bearings it is liable to do much damage and put the engine out of commission.

If the engine is a part of a fire truck 70 and is placed out of commission for this or any other reason, the truck would be unable to go to a fire until again placed in commission.

It is therefore very desirable that every 75 precaution should be taken to prevent injury to the engine and one means for accomplishing this is by renewing oil from time to time and keeping the oil that is in use free from sediment.

To this end a sediment collector such as the barrel 20 is provided which fits accurately the cylindrical chamber 15, this being closed at both ends and having an opening 21 in the wall thereof.

The opening 21 is adapted to register with the opening 14 so that any sediment in the oil may pass through these openings into the interior of the barrel 20.

Between the ends of the barrel 20 and the 90 inner ends of the closures 16 are placed packing disks 22 which are forced by said closures against the ends of the barrel 20 so tightly that said barrel is prevented from turning in the chamber 15.

A plurality of barrels 20 are kept on hand and when sufficient sediment has collected in the barrel in use and it is desired to clean the same, both closures 16 are removed and an empty barrel is inserted into the end of 100 the chamber 15 against the end of the barrel in said chamber.

By applying force to the inserted barrel the filled barrel may be pushed through the

chamber 15 and removed from the opposite end thereof, the inserted barrel taking the place of that removed.

The closures 16 are then replaced and the 5 engine is in condition immediately for further use.

The sediment in this manner may be removed from each of the troughs without interference with either of the others, it being 10 understood that the crank casing is provided with a plurality of troughs, each with its own sediment collector or barrel 20.

In another application of mine, Serial No. 732,741, filed August 18, 1924, is shown a 15 means of removing the entire trough through the wall of the casing, but many engines now in use have their crank casings provided with troughs formed integral therewith and which cannot be removed from the 20 casing.

It is difficult to get at such troughs for the purpose of cleaning them or freeing them from sediment.

By means of the construction herein 25 shown and described this can be accomplished readily without obtaining access to the interior of the casing.

As a consequence much time and labor are saved as heretofore the entire casing 30 must be dismantled.

It is obvious that the sediment may be removed from the troughs without interfering with the operation of the engine, that is, the engine may continue in opera- 35 tion while the barrel is being removed and another barrel is being inserted.

It is believed that the operation and many advantages of the invention will be understood without further description.

40 Having thus described my invention, I claim—

1. A crank casing provided with a splash trough having a chamber extending lengthwise thereof from side to side of said casing and communicating by a passage with the oil-containing compartment of said trough; a removable barrel in said chamber closed at both ends and provided with an opening normally registering with said passage; and closures for the opposite ends of said chamber.

2. A crank casing provided with a splash trough having a chamber extending lengthwise thereof from side to side of said casing and communicating by a passage with the oil-containing compartment of said trough; a removable barrel in said chamber closed at both ends and provided with an opening normally registering with said passage; and closures threaded to the walls of said casing and adapted to close the opposite ends of said chamber.

3. A crank casing provided with a splash trough having a cylindrical chamber ex- 65 tending lengthwise thereof from side to side

of said casing and communicating by a passage with the oil-containing compartment of said trough; a cylindrical removable barrel in said chamber closed at both ends and provided with an opening normally 70 registering with said passage; and closures for the opposite ends of said chamber adapted to impinge upon the opposite ends of said barrel.

4. A crank casing provided with a splash 75 trough formed integral therewith having a chamber extending lengthwise thereof from side to side of said casing and communicating by a passage with the oil-containing compartment of said trough; a removable 80 barrel in said chamber closed at both ends and provided with an opening normally registering with said passage; and closures for the opposite ends of said chamber.

5. A crank casing provided with a splash 85 trough formed integral therewith and having a chamber extending lengthwise thereof through the opposite walls of said casing; means for closing the opposite ends of said chamber; and a removable sediment collector in said chamber closed at both ends and provided with a peripheral opening to receive the sediment settling to the bottom 90 of said trough.

6. A crank casing provided with a splash 95 trough having an oil compartment with a curved bottom communicating at its lowest part with a cylindrical chamber extending from side to side of the casing; a sediment collector extending lengthwise of said chamber and adapted to be removed by the insertion of another sediment collector; and closures for the opposite ends of said chamber.

7. A crank casing provided with a splash 105 trough having an oil compartment with a curved bottom communicating at its lowest part with a cylindrical chamber extending from side to side of the casing; a removable barrel closed at both ends extending 110 lengthwise of said chamber and adapted to be removed by the insertion of another barrel; and closures for the opposite ends of said chamber.

8. A crank casing provided with a splash 115 trough having an oil compartment with a curved bottom communicating at its lowest part with a cylindrical chamber extending from side to side of the casing; a barrel closed at both ends extending lengthwise of said chamber and adapted to be removed by the insertion of another barrel, said barrels being provided with peripheral inlets through which the sediment may pass to the 120 interiors thereof; and closures for the opposite ends of said chamber.

Signed by me at 746 Old South Bldg., Boston, Mass., this 3rd day of February, 1925.

PARKER B. HASKELL.
